UNITED STATES PATENT OFFICE

MAX CHAMBERS AND ALBERT F. SISK, OF PRESTON, MARYLAND

PACKING MACHINE

Application filed November 6, 1929. Serial No. 405,148.

This invention relates broadly to packing machines, and has more particular reference to a packing machine for packing canned articles of food and the like into cardboard or wooden cases, boxes, containers, or the like.

A primary object of this invention is to provide in a machine of the character above mentioned, an improved pusher mechanism for urging the cans into the cases or boxes in 10 which they are to be packed for shipment.

A still further object of the invention is to provide a machine of this character also equipped with an especially designed holder for securing the cardboard cases or boxes, 15 which cases or boxes may be of any other desired material in a position to receive the canned food urged therein by the pusher.

A still further object of the invention is to provide a machine of this character wherein 20 the pusher mechanism is mounted on wheels or rollers to ride over a suitable track provided therefor, together with additional rollers placed on opposite sides thereof, the rollers on one side adapted to engage with the next 25 succeeding series or load of cans for arresting the movement of said cans while said pusher is in a steering position and the rollers or wheels on the other side of the pusher being in the nature of friction wheels to eliminate 30 any possible friction and to facilitate the operation of the pusher, and whereby the danger of tearing the labels on the cans or otherwise damaging the cans is practically eliminated.

A still further object of the invention is to provide a pushing mechanism of the character above mentioned, which may be easily operated either by hand, foot, or mechanical power.

Other objects and advantages of the invention will become apparent during a study of the following description, taken in connection with the accompanying drawings, 45 wherein:

Figure 1 is a top plan view of a packing machine embodying the features of this invention.

Figure 2 is a front elevation thereof.

Figure 3 is a vertical sectional view taken

substantially on the line 3—3 of Figure 2 and taken in the direction of the arrows.

Figure 4 is a horizontal section taken therethrough on the line 4—4 of Figure 2 and looking downwardly in the direction of the arrows.

Figure 5 is a vertical transverse sectional view taken substantially on the line 5—5 of Figure 2.

Figure 6 is a detail sectional view taken substantially on the line 6—6 of Figure 3.

Figure 7 is a detail sectional view taken substantially on the line 7—7 of Figure 2.

Figure 8 is a detail sectional view taken substantially on the line 8—8 of Figure 2.

Figure 9 is a fragmentary detail sectional view taken substantially on the line 9—9 of Figure 1.

Figure 10 is a fragmentary detail view of one modified form of can engaging roller.

Figure 11 is a similar view of still another modified form of can engaging roller.

With reference more in detail to the drawings, it will be seen that our improved machine comprises an elongated table of frame 75 construction and designated generally by the reference character T. This table comprises supporting legs 5 secured at their upper ends to spaced parallel longitudinal side frame members 6—6.

The side frame members 6 of the table at their rear ends are connected by a cross member 7 so that the table is substantially U-shaped in cross section.

Extending transversely across the table T 85 intermediate the ends of the table, are a pair of spaced parallel track supporting bars 8—8. As shown to advantage in Figure 2 these track supporting bars 8 extend laterally from opposite sides of the table, the bars 90 extending for a greater distance on one side of the table than on the other.

Supported on these bars 8 is a frame structure designated generally by the reference character F forming upper and lower guide 95 tracks as shown to advantage in Fig. 2. The upper guide tracks comprise the rails 9—9 and the lower guide tracks comprising the rails 10—10. The rails of the upper and lower tracks are formed of angle iron con- 100

struction, and the rails 10 of the lower guide tracks at their outer or entrance ends are curved upwardly and forwardly as at 11 to merge into the upper rails 9 inwardly from the forward end of the rails as also shown to advantage in Figure 2.

Supported on that portion of the bars 8-8 resting on the table T is a housing designated generally by the reference character H. This housing H comprises a bottom wall 12, a side wall 13, and a top wall 14. The housing is further divided into an upper compartment 15 and a lower compartment 16 at the rear end thereof through the medium of a horizontally disposed partition 17.

At their forward ends, the tracks 9 and 10 extend through the open side of the housing and into the housing to terminate at the rear wall of said housing. The ends of the upper tracks rest on the partition 17. The forward end of the lower track 10 rests upon the bottom wall of the housing. A pair of brace members 18-18 are arranged on one side of the track structure F and disposed one to each side of the table T, said brace members 18 at their upper ends converging toward one another to fit against the adjacent sides of the housing H, extending above the top of the housing.

At their upper ends, these brace members 18 are connected by cross brace rods 19. These brace members 18-18 being arranged in pairs, one pair to each side of said track structure provides a suitable framework for retaining the housing H in position.

At its forward end, and to one side of the frame structure F the housing H has a side wall section 13', thus cooperating the adjacent portion of the top wall 14, bottom wall 12 and the other first mentioned side wall 13 a substantially rectangular shaped structure constituting what may be termed a form or container holder designated generally by the reference character C. Over this portion of the housing designated as the container holder C may be slid a cardboard container, wooden box, or other similar receptacle as shown in dotted lines in Figure 3 so that the receptacle opens into the housing for a purpose to be hereinafter more fully set forth.

Suitable braces 21 may be employed for bracing the guide frame structure F and retaining the same in position upon the horizontal support bars 8.

As shown to advantage in Figure 3, the box holder or form C projects over a raised platform mounted on the forward end of the table and designated generally by the reference character P. The raised platform P may be of any suitable construction, but preferably is shown comprising a plurality of transverse bars 23 secured at their opposite ends to the frame members 6 and

longitudinal bars 24 preferably in the nature of elongated strips of metal resting upon and intersecting the bars 23, so that the platform P is in the nature of a grid.

The platform P may be utilized for resting the filled containers thereon after the latter have been removed from the form C.

Track rails 24-24 are disposed flush with the bottom 12 of the housing and extend from the opposite end of the housing, said rails at their opposite ends being supported on a cross bar 25. These rails 24 provide a trackway for a pusher carriage designated generally by the reference character R. This pusher carriage R is of the structure best shown to advantage in Figures 1 and 3 and comprises spaced parallel bottom frame bars 25 connected at their forward ends through the medium of a cross bar 26 and a pair of upper frame bars 27 connected at their forward ends through the medium of a cross bar 28.

The upper frame bars 27 have downwardly and rearwardly curved end portions 29 converging toward one another at their ends and are bolted to the rear end of a brace member 30 extending rearwardly from the intermediate portion of a cross brace member 31 connecting the rear ends of the lower frame members 25. Side brace members 32 are secured at their upper and lower ends to the upper and lower frame bars 27 and 25 respectively.

Supporting rollers 33 are mounted at the forward ends of the lower frame bars 25 and ride upon the track rails 24. Thus it will be seen from a study of Figure 3 that by moving the pusher carriage along its trackway to the left of Figure 3, the carriage will enter the housing H, the upper bars 27 extending into the housing and positioned within the compartment 15 and the lower frame bars 25 into the compartment 16.

The upper and lower cross frame bars 28 and 26 respectively at one end have suitably mounted thereon anti-friction rollers 34 as at 35 to engage with the inner face of the side wall 13. At their opposite ends, each of the said members 28 and 26 respectively are provided with upper and lower can engaging rollers 36 as also shown to advantage in Figure 2.

To permit the passage of the pusher carriage R through the housing H, the lower track rails 10-10 are suitably notched as at 10'-10' to permit the supporting wheels 33 to pass therethrough as also shown to advantage in Figure 2.

Between the rear end legs 5 of the table, and adjacent the lower ends thereof there is disposed a horizontal shaft 37. The ends of the shaft being secured in the said end legs 5. An elongated operating lever 38 has one end pivotally mounted on said shaft and this lever 38 inclines upwardly and forwardly to

extend beyond the adjacent forward end of the table as shown to advantage in Fig. 3.

The lever 38 is normally held in this position through the medium of a coil spring 39 one end of which may be anchored to one of the track frame supporting bars 8, and its other end secured to the lever 38 adjacent the pivoted end of the latter. A connecting rod 40 has one end thereof pivoted on the shaft 37 adjacent the pivoted end of the lever 38, and at its upper end the rod 40 is pivoted as at 41 to the rear end of the pusher carriage frame member 30. The lever 38 is connected to the operating rod 40 through the medium 15 of a link 42, the ends of which link are pivoted to adjacent end portions of the lever and connecting rod respectively.

Manifestly, when the lever 38 is in that position shown in Figure 3, being held there- 20 in under the action of the coil spring 39, the pusher carriage R will be disposed outwardly of the housing H or in that position also shown in Figure 3. When pressure is applied to the free end of the lever 38 for rock- 25 ing the same, the bar 40 will be rocked upon its pivot to move towards the left in Figure 3, thus forcing the pusher carriage R inwardly of the housing H.

To insure the retention of the pusher carriage R upon its trackway there is provided a suitable coil spring 43 anchored at one end to the pusher brace bar 30 and at its other end anchored to the table in any desired or well known manner. The cross member 7 of 35 the table will act as a stop against which the upper end portion of the operating bar 4 will abut while the lever 38 is drawn upwardly to its normal position for moving the pusher carriage outwardly of the housing.

As shown to advantage in Figures 4 and 7, cans shown in dotted lines and designated by the reference character 44 will move along the upper and lower tracks, the cans being in a canted position to roll along the rails of the 40 tracks and into the housing H. The upper and lower rails 9 and 10 at that end of the housing through which the pusher carriage enters and at that side of the housing through which the cans on the track enter, said tracks 45 are bowed or bent inwardly as at 45 and 46 respectively so that those cans within the housing which are to be moved lengthwise of the housing by the pusher carriage R are thrown forwardly or in the direction toward 50 the container support or form C, thus enabling the rollers 36 to engage the cans with ease, and hold the next charge of cans in place or from entering the housing so that the cans next to enter the housing will not interfere 55 with those cans being pushed through the housing to be moved into the container or the container supports or form C.

In this connection, of course, it is to be noted, and as shown to advantage in Figure 7, 60 the upper and lower rails 9 and 10 respec-

tively adjacent the receptacle carrier or form C do not extend through the housing but rather terminate at the sides of the housing. In this way no obstruction will be presented to the can and thus permit the upper and 70 lower series of cans to be slid across the bottom 12 and partition 17 into the container in which they are to be packed.

Extending upwardly and outwardly from the top wall 14 above the upper track is a 75 plate or head member 47 which engages the can to prevent jamming or piling up of the cans upon the track.

It is believed that from the foregoing description, taken in connection with the accompanying drawings, a clear understanding of the operation, construction, utility and advantages of a packing machine of this character will be had without a more detailed description. 80

In Figure 10 we have shown a modified form of can engaging roller, and as therein illustrated it will be seen that the roller is designated generally by the reference character 36a, and that the same is disposed in 90 a vertical position being journaled between the co-extensive arms b—b of a U-shaped bracket L mounted on the ends of the cross bars 26 and 28 respectively in lieu of the rollers 26 for engaging the cans for the same 95 purpose as the said rollers 26.

In Figure 11 we have shown a still further modification of these can engaging rollers, and as therein illustrated the can engaging roller is designated by the reference character 36b and is to be mounted in a U-shaped bracket in the same manner as the can engaging roller 36a. However, it will be noted that the can engaging roller 36a tapers inwardly from its opposite ends and conforms somewhat to the contour of the can which it engages, while in the last instance, that is, the roller 36b may be of uniform diameter throughout its entire length. However, either of these forms will be found to be 100 well adapted for the purpose designed and their intended use. 110

It is also apparent that a machine of this character will be comparatively simple in construction, the same consisting of but comparatively few parts, and further, it is to be understood that the machine can be built to accommodate any size can, and that while we have shown but two can tracks, we do not wish to limit ourselves to this particular number 115 since it is apparent that any number of tracks may be used, and that the invention is susceptible to certain other changes as come within the spirit of the invention as herein described, and the scope of the appended 120 claims. 125

Having thus described our invention, what is claimed as new is:

1. In a machine of the class described, a 130 supporting table, a raised platform mounted

on said table adjacent one end of said table, a guide frame structure extending transversely of said table intermediate the ends of said table, said frame structure comprising upper and lower tracks over which cans are adapted to move, a housing mounted on said table adjacent one end of said platform, and through which said upper and lower tracks extend, said housing at one side of the track being formed to provide a receptacle supporting form projecting above said platform, the rails of said upper and lower tracks remote from said receptacle supporting form within said housing being pressed inwardly for directing the cans on said track within said housing forwardly toward said receptacle supporting form, a trackway mounted on said table on the opposite side of the first mentioned tracks in longitudinal alinement with said housing, a wheel supported carriage movable on the last mentioned trackway, said wheel supported carriage comprising upper and lower cushion members adapted to extend transversely of said upper and lower tracks respectively, when said carriage is moved inwardly of said housing toward said receptacle supporting form, anti-friction rollers carried by said upper and lower pusher members for engagement with the adjacent wall of said housing, additional rollers carried by said upper and lower pushing members adapted to engage with certain of the cans on said upper and lower tracks when said pusher carriage is moved toward said receptacle supporting form to arrest the movement of the last mentioned can when the cans engageable by said pusher member are being urged into the receptacle on said supporting form.

2. In a machine of the class described, a supporting table, a raised platform mounted on said table adjacent one end of said table, a guide frame structure extending transversely of said table intermediate the ends of said table, said frame structure comprising upper and lower tracks over which cans are adapted to move, a housing mounted on said table adjacent one end of said platform, and through which said upper and lower tracks extend, said housing at one side of the track being formed to provide a receptacle supporting form projecting above said platform, the rails of said upper and lower tracks remote from said receptacle supporting form within said housing being pressed inwardly for directing the cans on said track within said housing forwardly toward said receptacle supporting form, a trackway mounted on said table on the opposite side of the first mentioned tracks in longitudinal alinement with said housing, a wheel supported carriage movable on the last mentioned trackway, said wheel supported carriage comprising upper and lower cushion members adapted to extend transversely of said upper and lower tracks respectively, when said carriage is moved inwardly of said housing toward said receptacle supporting form, anti-friction rollers carried by said upper and lower pusher members for engagement with the adjacent wall of said housing, additional rollers carried by said upper and lower pushing members adapted to engage with certain of the cans on said upper and lower tracks when said pusher carriage is moved toward said receptacle supporting form to arrest the movement of the last mentioned can when the cans engageable by said pusher member are being urged into the receptacle on said supporting form, a lever pivotally mounted on said table, means operatively connecting said lever with said pusher carrier, whereby when said lever is rocked, said pusher carriage may be moved into or out of said housing for urging the cans on said trackways into said container.

3. In a machine of the class described, a supporting table, a raised platform mounted on said table adjacent one end of said table, a guide frame structure extending transversely of said table intermediate the ends of said table, said frame structure comprising upper and lower tracks over which cans are adapted to move, a housing mounted on said table adjacent one end of said platform, and through which said upper and lower tracks extend, said housing at one side of the track being formed to provide a receptacle supporting form projecting above said platform, the rails of said upper and lower tracks remote from said receptacle supporting form within said housing being pressed inwardly for directing the cans on said track within said housing forwardly toward said receptacle supporting form, a trackway mounted on said table on the opposite side of the first mentioned tracks in longitudinal alinement with said housing, a wheel supported carriage movable on the last mentioned trackway, said wheel supported carriage comprising upper and lower cushion members adapted to extend transversely of said upper and lower tracks respectively, when said carriage is moved inwardly of said housing toward said receptacle supporting form, anti-friction rollers carried by said upper and lower pusher members for engagement with the adjacent wall of said housing, additional rollers carried by said upper and lower pushing members adapted to engage with certain of the cans on said upper and lower tracks when said pusher carriage is moved toward said receptacle supporting form to arrest the movement of the last mentioned can when the cans engageable by said pusher member are being urged into the receptacle on said supporting form, a lever pivotally mounted on said table, means operatively connecting said lever with said pusher carrier, whereby when said lever is rocked, said pusher carriage may be moved into or out of said housing for urging the cans on said trackways into said container.

rocked, said pusher carriage may be moved into or out of said housing for urging the cans on said trackways into said container, and spring means normally urging said lever in one position for moving said pusher carriage rearwardly from across said tracks.

4. In a machine of the class described, a supporting table, a raised platform mounted on said table adjacent one end of said table, a guide frame structure extending transversely of said table intermediate the ends of said table, said frame structure comprising upper and lower tracks over which cans are adapted to move, a housing mounted on said table adjacent one end of said platform, and through which said upper and lower tracks extend, said housing at one side of the track being formed to provide a receptacle supporting form projecting above said platform, the rails of said upper and lower tracks remote from said receptacle supporting form within said housing being pressed inwardly for directing the cans on said track within said housing forwardly toward said receptacle supporting form, a trackway mounted on said table on the opposite side of the first mentioned tracks in longitudinal alinement with said housing, a wheel supported carriage movable on the last mentioned trackway, said wheel supported carriage comprising upper and lower cushion members adapted to extend transversely of said upper and lower tracks respectively, when said carriage is moved inwardly of said housing toward said receptacle supporting form, anti-friction rollers carried by said upper and lower pusher members for engagement with the adjacent wall of said housing, additional rollers carried by said upper and lower pushing members adapted to engage with certain of the cans on said upper and lower tracks when said pusher carriage is moved toward said receptacle supporting form to arrest the movement of the last mentioned can when the cans engageable by said pusher member are being urged into the receptacle on said supporting form, a lever pivotally mounted on said table, means operatively connecting said lever with said pusher carriage, whereby when said lever is rocked, said pusher carriage may be moved into or out of said housing for urging the cans on said trackways into said container, and spring means normally urging said lever in one position for moving said pusher carriage rearwardly from across said tracks, yielding means engageable with said carriage for retaining said carriage on its trackway, and means for limiting the movement of said carriage in one direction.

5. A packing machine including in combination, a housing, a trackway extending through said housing, said housing laterally of said trackway provided with an integral container supporting form, certain of the rails of said trackway being passed inwardly

for directing cans on said trackway laterally of the latter toward said supporting form, and means engageable with the cans for transferring the cans from said trackway into the container supported on said form.

6. A packing machine comprising in combination a trackway, adapted to have moved thereover cans to be packed, certain of the rails of said trackway being pressed inwardly for normally urging the cans laterally of the trackway, a second trackway laterally of the first mentioned trackway, a wheel supported carriage movable on the last mentioned trackway, said carriage including pusher members adapted to extend transversely of the first mentioned trackway when said carriage is moved toward said first mentioned trackway, said pusher members being adapted to engage the cans for ejecting the latter from said first mentioned trackway.

7. A packing machine comprising in combination a housing, upper and lower can supporting tracks extending through said housing, a box supporting form integral with said housing laterally of said upper and lower trackways, said upper and lower trackways respectively having the rail thereof remote from said box supporting form pressed inwardly for normally urging the cans on said trackway laterally of the trackway toward said box supporting forms.

8. A packing machine comprising in combination a housing, upper and lower can supporting tracks extending through said housing, a box supporting form integral with said housing laterally of said upper and lower trackways, said upper and lower trackways respectively having the rail thereof remote from said box supporting form pressed inwardly for normally urging the cans on said trackway laterally of the trackway toward said box supporting forms, means movable transversely of said upper and lower trackways for engaging certain of the cans for transferring said cans from said upper and lower trackways into the box on said supporting forms, said means also including means for engaging other of the cans on the trackways for arresting movement of the last mentioned cans during packing operation.

In testimony whereof we affix our signatures.

MAX CHAMBERS.
ALBERT F. SISK.
